UNITED STATES PATENT OFFICE.

DAVID BASCH, OF NEW YORK, N. Y.

DESIGN FOR A TOE-CLIP FOR VELOCIPEDES.

SPECIFICATION forming part of Design No. 26,284, dated November 17, 1896.

Application filed September 9, 1896. Serial No. 605,383. Term of patent 7 years.

To all whom it may concern:

Be it known that I, DAVID BASCH, of New York, county and State of New York, have invented and produced a new and original 5 Design for Toe-Clips for Velocipedes, of which the following is a full, clear, and exact description.

Reference is to be had to the accompanying drawings, forming a part of this specification, 10 in which similar characters of reference indicate corresponding parts in both the figures.

Figure 1 is a perspective view of a toe-clip embodying my new design, and Fig. 2 is a front view slightly tipped up.

15 A leading feature of my design resides in the clip return-bent and tapered, the clip having a wide opening *a* at the bend and opposite lugs *b b* on the upper horizontal member of the clip, the lugs producing a for-

wardly-extending contracted opening extending from the wide opening *a* and communicating with the latter, the lugs rising in an inclined direction toward each other above the plane of the upper horizontal member on which they are formed. 20

Another leading feature consists in the clip return-bent, as shown, and with the wide opening *a*, as specified, the bent members at the sides of said opening presenting diagonal corrugations *c*. 25

I claim—

The design for a toe-clip herein shown and described. 30

DAVID BASCH.
